UNITED STATES PATENT OFFICE

170,158

ILLUMINABLE FLORAL AQUARIUM

Charles E. Jones, Chicago, and Robert H. Crowle, Berwyn, Ill., assignors, by mesne assignments, to Emanuel J. Rice and Al B. Wolf, doing business as Flora-Lite Company, Chicago, Ill.

Application September 9, 1952, Serial No. 21,391

Term of patent 7 years

(Cl. D91—2)

To all whom it may concern:

Be it known that we, Charles E. Jones and Robert H. Crowle, citizens of the United States, residing at Chicago and Berwyn, respectively, in the county of Cook and State of Illinois, have invented a new, original, and ornamental Design for an Illuminable Floral Aquarium, of which the following is a specification, reference being had to the accompanying drawing, forming a part thereof.

In the drawing:

Fig. 1 is an elevation view of an illuminable floral aquarium showing our new design; and Fig. 2 is a plan view.

The essential features of our design reside in the portions shown in full lines.

We claim:

The ornamental design for an illuminable floral aquarium, substantially as shown and described.

CHARLES E. JONES.

ROBERT H. CROWLE.
